UNITED STATES PATENT OFFICE.

EDWARD E. CLEMENT, OF WASHINGTON, DISTRICT OF COLUMBIA.

TELEPHONE-EXCHANGE SYSTEM.

1,105,545.

Specification of Letters Patent.

Patented July 28, 1914.

Application filed April 10, 1914. Serial No. 831,048.

To all whom it may concern:

Be it known that I, EDWARD E. CLEMENT, a citizen of the United States, residing at Washington, in the District of Columbia, have invented certain new and useful Improvements in Telephone-Exchange Systems, of which the following is a specification, reference being had therein to the accompanying drawing.

10 My invention relates to operator's automatic controlling apparatus for automatic switches of the various types used in automatic and semi-automatic telephone systems, and particularly to the latter, to enable the operator to directly control the connection of a calling to a called line, by pre-determination, coincidently with the reception of the number of the called line, and without waiting for the various switches to complete their several operations.

The apparatus and system shown herein are in part disclosed in several prior applications of mine, including among others, one filed March 30, 1906, Serial No. 309,010.

25 Of the drawings Figure 1 is a diagram of subscribers' lines and operators' cord circuits, Fig. 2 is a diagram of the operators' controlling apparatus which is in this system associated with the operator's cord circuit, Fig. 3 is a diagram of an automatic connector switch and trunk adapted to be connected to the cord circuit and in turn to be controlled by the operator through the apparatus aforesaid to connect with a called line, Figs. 4 and 5 show in diagram a modified form of my invention in which a multiple number of key sets are associated commonly with a single set of independently characterized control circuits of the sending machine, Figs. 6, 7 and 8 are plan, and side and end elevation respectively of a row of the push button keys of the key sets showing their structural details.

40 Referring to the drawings and particularly to Fig. 1, A is a subscriber's station having the usual subscriber's common battery outfit, consisting of transmitter, receiver, switch-hook, ringer and condenser. From this substation the line-wires 1-2 extend to the central office, where they pass through the contacts of the cut-off relay, M', which normally connects them to the line-relay M and ground, respectively. This line relay is connected on the other side to the main battery, B, and controls a signal lamp, L, associated with the answering-jack,

5 J. The answering-jacks, J, are supposed to be grouped in a convenient manner, together with their signal lamps, L, in front of the operators, and when any line is calling it is intended that it shall be connected through a trunk-jack, J', with a trunk-line leading to an automatic switch, S, (see Fig. 3), by which the subscriber wanted can be directly reached. In order to interconnect the line and trunk-jacks I provide a pair of plugs, P, P', having their tips and sleeves respectively connected through the conductors 3-5 and 4-6, these conductors being interrupted for direct currents by the condensers, C. The answering plug, P, has associated with it a supervisory signaling lamp, L' directly controlled by the tip relay, R, which responds to current in the subscriber's line as long as the plug is in a jack; the lamp is also indirectly controlled by the sleeve relay, R', which puts battery on the armature of the tip relay when the plug is first inserted. Current through the sleeve relay is also necessary in order to 60 energize the cut-off relay, M', of the line in making connection therewith. The calling plug, P', has three contacts, which I may call the tip, p, the ring, p', and the sleeve, p'', the ring in this case corresponding to the sleeve of the plug P. When the plug is inserted in a trunk-jack, J', the tip and ring come into connection respectively with the jack springs, j, j', while the sleeve, p'', comes into contact with a thimble, j'', connected 65 through a resistance, j', to ground. This thimble is for test and also to furnish a circuit for the cord cut-off relay, R''. There are two relays, R'', R'', associated together for controlling the connection of the operator's telephone. The relay, R'', takes current through the wires 17 and 18 when the plug, P, is first inserted in answer to a call, the circuit—B, 19, 17, 18 and ground being then 70 immediately closed by the relay R', pulling up. Thereupon the relay, R'', immediately pulls up, the relay, R'', which also controls it remaining quiescent. In so pulling up it closes the two sides of the operator's secondary circuit —9—10— onto the bridge wires 7—8 across the cord-conductors 3—4. This secondary circuit contains the operator's receiver, T', and the secondary winding, i, of the induction coil, I. The primary, i' is included in a short-circuit 13—14 75 with the condenser, C', and the transmitter, T, the latter deriving its current supply di-

rect from the main battery through the choke-coil, i^3 by the circuit—B, 20, 21, 22 and ground. The tertiary winding i^2 , is included in the test circuit 11—12, which 5 passes from ground through a back contact on the relay, R^2 , to the tip conductor 5 and so to the tip of the calling plug, P' .

The trunk-lines 23—24, which terminate in the jacks, J' , are each multiplied to all 10 the sections of the switchboard, so that any operator can reach any trunk. The trunks are arranged in groups, those of each group leading to similar switches in which the same group of subscribers' line-wires are 15 multiplied. This is necessary so as to always have enough idle trunks and switches to reach a number of subscribers of the same group at the same time. Each connector switch is supposed to contain the terminals 20 of one hundred lines, and as a fair average I may assign ten switches to each one hundred lines, so as to be able to call ten subscribers out of that particular hundred at the same time. All of these subscribers' 25 lines are multiplied into the ten switches, and the ten trunks from the ten switches are carried together to the switchboard, where they are multiplied and have their jacks appear 30 together in a group on all the switchboard sections. These jacks may be arranged in a continuous line either vertically or horizontally, so that in testing to find an idle trunk, the operator will simply run the tip 35 of her plug down the row in the group desired. These groups are numbered from 0 to 99, which means that through the trunks of No. 0 group the subscribers' lines whose numbers are from 0 to 99 can be reached; through No. 1 group those whose numbers 40 are from 100 to 199 can be reached; through No. 2 group those whose numbers are from 200 to 299 can be reached, and so on up to 45 9999, or if it be desired to carry it so far, even to 99,999, which would of course require 10,000 multiple jacks per section of 50 three operator's positions, which is the same as in a ten thousand multiple-board now. In other words, the same multiple-board which now serves 10,000 subscribers can be 55 cut over by my present invention to accommodate 100,000 subscribers, at least so far as regards the multiples. In actually reconstructing such a board, it would be necessary to increase the number of answering-jacks, and also of cords and plugs since the operators will handle a great many more calls than before.

In answering a call and making the connection the operator proceeds as follows: 60 Seeing the lamp L , light, she inserts plug P into the corresponding jack, J , whereupon the battery B , sends current at once through the sleeve relay R' , and the cord-conductor 4 to the line-extension 25, to the cut-off relay 65 M' and ground. The cut-off relay thereupon

pulls up, putting the line-wires 1—2 onto their extension 26 and 25 and thence onto the cord-conductors 3 and 4, whereupon relay R pulls up and opens the conductor leading to the lamp L' which had just been closed by the relay R' , the entire action being too quick for the lamp to have time to light. At the same time relay R^2 pulls up 70 and the operator's set, O , is bridged across the answering cord, while the test wire 75 11—12 remains connected to the tip of the calling plug. The operator picks up the plug P' and at the same time asks "Number?" Ascertaining the number, she tests 80 with the plug P' , the trunk-jacks corresponding to the hundreds of the line wanted, by running the tip, p , along the row of thimbles, j' , until she no longer gets a click. If any trunk is busy, having a plug in it, the potential of its jack thimbles, j^2 , will be 85 raised by main battery B , through the circuit—19, 27, 28 and the relay R^2 . Hence the tip of the testing plug will take current off of this through the conductors 5, 12 and 11 to the testing operator's tertiary winding 90 i^2 , this producing a click in the receiver, T' , each time the tip, p , passes over a charged or busy thimble. Having reached a jack which produces no click, the operator puts 95 in the plug, P' . Relay R^2 pulls up, the operator's telephone is disconnected and the test circuit of that plug is broken. This much of the operation is substantially the same as in any manual system, substituting 100 trunk-jacks for line-multiples, of course. The balance of the operation, however, is 105 entirely different. The trunk 14—13 shown in the diagram, leads to the connector switch S , shown in Fig. 3, and this switch is operated by means of impulses over the 110 two sides of the trunk, in a manner which is generally familiar to those acquainted with the art. In order to do this I provide the operators with impulse transmitters or 115 "senders." These devices I term multiple signal senders. The term multiple applies first because the device has the power to produce and send simultaneously a plurality of series of signal impulses; and second because in each cycle of operation of the device these series of impulses are each produced a plurality of times.

It will be obvious from the following disclosure of the operation of this device that in each cycle of the multiple signal sender the conditions of proper electrical potential for a plurality of simultaneous series of impulses and for the repetition of each of these series of impulses are produced upon the leading out wires or bus wires, whence by the proper provision of path for current through auxiliary signal selecting means, current impulses may be taken corresponding to any one of the series of potential impulses of the signal sender, or corresponding to a plu- 120 125 130

rality of such series. For convenience I will first describe this arrangement as it is shown in Fig. 2, and will then proceed to point out its effect upon the apparatus of Fig. 3. In 5 this figure Q^0 , Q , Q' , Q^2 , Q^3 , Q^4 , Q^5 , etc., are a set of wheels mounted on and turning with a common shaft, which may be driven in any suitable manner. The wheel Q^0 , puts battery and ground alternately on the wire 29, 10 which for purposes of illustration represents the metallic shaft connection between the wheels. The wheel Q is insulated from the shaft and is grounded, has an insulating spot in its periphery, and controls by 15 means of this spot the locking and unlocking wires 30 and 31, in a manner which will appear from the statement of operation. The wheels Q' , Q^2 , Q^3 , Q^4 , etc., are number-wheels, the first one having one tooth, the 20 second two teeth and so on up to ten teeth. (For simplicity of illustration only 5 wheels are shown.) Around these wheels are three sets of pens, connected to the three sets of keys, K' , K^2 , K^3 . Circuits including 25 any set of pens and the associated number wheels are thus both independently and differently electrically characterized. As the wheels revolve from the position in which they are shown in the figure, they first make 30 contact with the upper pens, q' , then with the pens, q^2 , then with those, q^3 . The first set with their buttons or keys, K' transmit the tens digits of any number, the next set 35 transmit the units digit, and the third set transmit the ringing number. All this will appear more clearly from the statement of operation.

The keys, K' , K^2 , K^3 are of the so-called self-latching selective ringing type now in 40 common use on manual switch-boards, and employ the principle shown in the patent to Ham, No. 605,097 granted June 17, 1898. When any key is pressed down it pushes back the latch and releases the one that was 45 previously down, then latching itself. It will be noted that the bank of keys is divided into three sets or rows, K' , K^2 and K^3 respectively. The rows are each provided with the latching device of Ham, cited, the rows being 50 independent of each other in this respect; thus one key and only one of each row will remain depressed, the previously depressed key of each row being released by the depression of any other. In a bank or 55 row of keys of this nature, a key is depressed through a travel carrying it beyond the locking point; upon release it returns a very short distance and remains locked there until released by the depression of the next key 60 used. I take advantage of this detail in the row of keys K^3 in the following manner: The pairs of springs as k^4 are to remain locked when the key is pressed, as described later, but the triple springs k^6 are springs 65 requiring but a momentary contact to ener-

gize primarily the pair of locking relays R^4 , R^5 . To secure the desired end, I so gage the relation of the springs k^6 to the push button of the key that they are closed by the button when at its point of farthest travel but are released by the slight return travel of the button before it is locked. The springs k^4 however remain closed until the button is unlocked and fully released. Each 70 set of keys has a common wire, this for the sets K' , K^3 , being marked 32, these two being joined together and carried to a back contact of the relay, R^4 , while that for the set K^2 , is marked 38 and carried to another back contact of the same relay. The numbers to be sent are set up by depressing the 75 keys, one of each row, the key on row K^3 being depressed last, and the act of depressing that key serving to energize and lock the relays R^4 , R^5 , and then the signal is 80 started at the beginning of a rotation of the shaft, when the first tooth of each wheel is about to strike its pen q' , by the relay, R^4 , being deenergized, while the relay, R^5 , remains energized. The means of this is in 85 the arrangement of the spring pens, q^5 , q^6 , on the wheel Q . This wheel is rotated with the others in the direction of the arrow, and its insulating spot passes first under the spring pen, q^5 , momentarily cutting ground 90 off of that and the wire 31, then subsequently under the pen, q^6 , taking ground off of that.

In calling the number wanted, which we will assume to be 32-3, the operator plugs 100 into the calling line jack, then presses down button No. 3 of the set, K' ; No. 2 of the set, K^2 , and No. 3 of the set, K^3 . The buttons of the sets, K' and K^2 have their several individual wires connected to the springs or 105 pens q' , q^2 , on the several individual wheels, Q' , Q^2 , etc., and the effect of pressing down the buttons as mentioned is to connect the pen q' of the wheel, Q^3 through the springs, k' of the button k to the wire 32. At the 110 same time the pen, q^2 , of the wheel Q^2 is connected through the springs, k^2 , of the button k^2 to the wire 33 and the spring, q^3 , of the wheel, Q^2 , is connected through the springs, k^4 of the button, k^6 , to the wire 32. 115 The set of buttons, K^3 , also have the starting springs, k^5 . This set of buttons being the last, or ringing set, the number is ready for transmission when any one of them is depressed, hence any one of these buttons 120 not only finishes setting up the number, but by closing the springs k^6 , puts ground momentarily on the starting wires 37 and 38, which pass to the two relays, R^4 , R^5 , respectively, and thence through the common return wire 39 to battery B and ground. Both the relays pull up, and both lock, the locking circuit of the relay, R^4 , being as follows: B, 39, R^4 , r^6 , 30, q^6 , Q and ground. The locking circuit of R^5 is as follows: B, 39, R^5 , r^7 , 125 B.

31, q^5 , Q and ground. Having thus set up the signal and put it in condition to be started at the beginning of a revolution of the main shaft, and having also plugged into 5 the necessary hundreds group, the operator's work is finished. She pays no further attention to the connection until the subscribers have completed their conversation and have hung up, whereupon the relay, R' , in 10 Fig. 1 lets go, and the lamp, r lights to call for disconnection. The operator then pulls the plug, P.

The signal having been set up as described, the apparatus of Fig. 2 then operates as follows: The wheel, Q, in revolving will bring 15 the insulating spot under the pen, q^5 , at first, and might thereby cut off the relay, R^5 , prematurely, but this is provided for by making a branch locking circuit 310 which is 20 controlled through a contact of the armature, r^6 , and a ground wire 36 of the starting relay R^4 . Hence as long as the relay, R^4 , is energized, the relay, R^5 , cannot be affected. Moreover, it will be observed that the wires 25 32 and 33 remain disconnected from the wires 15-16 until the relay R^5 is energized, while the relay R^4 is deenergized. This condition is brought about when the insulating spot reaches the pen q^6 . The relay R^4 , 30 then lets go, and we have a continuous circuit from wire 32 as follows: 32, r' 34, r^3 , 16, 5 (in Fig. 1) and to trunk-wire 23. We also have a circuit for wire 33 as follows: 33, r^2 , 35, r^4 , 15, 6 (Fig. 1) and the other trunk-wire 24. The insulating spot reaches the 35 pen, q^6 , just before the first tooth on each wheel reaches its pen, q^7 ; hence as soon as the above desired condition is attained, the set of impulses which has been determined 40 by the key k , of the set K' comes from battery through Q⁰ and wire 29 through commutator and key and thence over the wire 32 to the wire 16 and so onto the wire 23 of the trunk, through which it passes into Fig. 3 to 45 the relay, R^6 , which will be presently described, and which I shall call for convenience the vertical relay. At the end of this group of impulses, the teeth on the wheels will have gotten around to the pens q^8 , and 50 so the next group of impulses determined by the k^2 , will pass from ground through the wheel Q⁰ and wire 29 through commutator and key and thence onto the wire 33 and so to the wire 15 and the trunk-wire 24, 55 through which they reach the relay R' , in Fig. 2, which will also be presently described and which I shall for convenience call the rotary relay. The names of these two relays are quite accurate in this system, 60 because the relay R^6 does really produce a vertical motion of the switch S, while the relay R' produces a rotary motion thereof. At the end of this second group of impulses, the teeth on the wheels have gotten around 65 to the third set of pens, q^9 , and the impulses

determined by the key k^5 , then come, from battery through wheel Q⁰ and wire 29 through commutator and key and thence through the wire 32 onto the wire 16 and so again to the trunk-wire 23 and to the vertical 70 relay, R^6 . After this, the insulating spot on the wheel, Q, reaches the spring, q^5 , and momentarily cuts off the ground therefrom. Since the relay, R^4 , is already deenergized, this breaks the locking circuit of the relay, 75 R^5 , and it lets go, disconnecting the wires 15-16 from the wires 35-34, and leaving the apparatus free from the talking wires 23-24 of the trunk. It may be stated here that each cord pair is equipped with a pair 80 of relays R^4-R^5 and a bank of keys K'-K²-K³ individual to that cord pair, but that the commutator shaft and its series of wheels is common to all cord pairs and connectors in the entire exchange. 85

Referring now to Fig. 3, I will briefly describe the switch operation. The switch, S, is shown only in diagram, but in so far as its mechanical features are concerned it is of the type shown in the following patents: 90 Keith and Erickson, 815,176, and 815,321, granted March 13, 1906. The circuits I employ in the present case are entirely different from those of these patents, but the mechanical structure is so far the same that 95 I employ a vertical spindle, s, which carries wipers, s', to coöperate with the line-terminals s², (see Fig. 1) or line-multiples, in the switch-banks; the switch spindle is set up step by step by the vertical magnet, 100 s³, and is rotated step by step by the rotary magnet, s⁴, controlled respectively by the relays, R^6 and R^7 . There are supposed to be one hundred pairs of line-terminals in the switch-banks, and I do not require any separate test terminals, since I test directly on the tip side of the line for a ground. The switch spindle controls a pair of springs, s⁵, which it opens when it is down in its normal position of disuse, for restoring purposes, as 110 will presently appear. s⁶ is the release magnet of the switch, which when energized removes the detent pawls from the respective ratchets of the spindle, s, allowing the spindle to drop down and rotate back to zero, 115 as fully described in the patents referred to. This release magnet is under the control of the relay, R^{10} , which in turn is controlled by the relays, R^6 and R^7 . It is also under the control of the test relay R^{11} . R^{12} is a 120 ringing selector control relay, R^{13} is a trunk cut-off relay and R^{14} is a ringing relay controlled by the commutator, X, which is common to the entire exchange and is mounted upon the shaft carrying the wheels Q⁰, Q, Q', etc., of Fig. 2 or is mounted to revolve in synchronism with that shaft and its commutator wheels. R^{15} is a slow acting relay, 125 preferably a solenoid, which connects the test relay, R^{11} , at the moment of effecting 130

connection, as controlled by the first ringing impulse, and at the same time opens the generator circuit, 40-41, while the proper current is being selected. R¹⁶ to R²¹, inclusive, are selective relays for enabling one or the other of the ringing generators, G, G', G² and G³, to be connected onto the ringing contacts of the ringing relay, R¹⁴, the particular generator being determined by the number of impulses received through the ringing-selector control relay, R¹², which operates the relays, R¹⁶, R¹⁹, R²⁰, R¹⁷, R²¹, R¹⁸, or as many of them as are desired in succession, each of them locking as it operates.

The operation of this trunk scheme is as follows: In selecting the number we have assumed 32-3; the trunk itself corresponds to the number 44, we have first three battery impulses coming over the wire to the relay, R⁶, followed by two ground impulses over the wire to the relay, R⁷, and then three battery impulses again over the wire to the relay R⁶. The first battery impulses coming over the wire caused the relay R⁶ to pull up three times, each time closing the following circuit: B, 42, 43, 44, s³, 45, 46, 47, and ground to battery. The vertical magnet, s³, steps the spindle, s, of the switch up three steps, so that the wipers s', stand opposite the third row of contacts. Two ground impulses then come over wire, affecting the relay, R⁷, which pulls up twice, the first time closing the following circuit: B, 42, 48, R⁹, 49, 50, armature of R¹⁰, 51 to ground and to battery. The relay, R⁹, instantly pulls up, cutting off the vertical magnet, s³, and locking itself by the following path: B, 42, 48, R⁹, r⁹, 52, 50 51 and ground back to battery. The vertical magnet, s³, is therefore cut off for the rest of the transmission. The rotary magnet, s⁴, however, gets current each time the relay, R⁷, is energized, over the following path: B, 42, 43, 44, s⁴, 53, 54, 55 and ground back to battery. The rotary magnet, s⁴, turns the spindle, s, two steps, so that the wipers s' rest on the second pair of contacts in the third row, or No. 32. Three battery impulses now come over the wire 23, causing the relay, R⁶, again to pull up three times. Each time it closes the following local circuit: B, 42, 56, R¹², 57, 46, 47 and ground back to battery. As a branch of this same circuit, the wire 58 comes in from the battery wire 42 through the solenoid R¹⁵ to 57, 46, 47 and ground. At this point in the development of the connection immediately following the closure of the contacts of relay R⁶ at the beginning of the first generator-selection impulse, two things occur simultaneously.

(1) The solenoid R¹⁵ attracts its core, opening the wires 40-41 and closing the switch 62 whereby a test circuit is formed

through elements B, 42, 62, R¹¹, 63 to upper s', which at this moment is resting in contact with the line selected through the agency of vertical and rotary magnets s³ s⁴. If the line be busy then a circuit will exist from upper wipers s' to the tip of the plug and through the relay R to ground in case the line tested has called or to another wiper s' and thence through a trunking equipment following the path through contact of R¹⁴, 75 contact R¹³, conductor 23 and winding of R⁶ to ground if that line has been called; in either case the test relay R¹¹ will be energized and in turn will energize the release magnet s⁹. If, however, the selected line 80 with which the test wiper rests in contact is not busy no circuit will exist from that test wiper to ground and the test relay R¹¹ will not be energized; a branch path for the conductor 63 exists through the talking conductor of the trunk to the left hand contact of relay R¹⁴ and thence to an armature contact of relay R¹² where it terminates open, but subsequent to the energization of relay R¹⁴ as about to be described, this branch 85 path passes to the inner contact of the left-hand armature of that relay and thence over the conductor 41 to the right hand switch of the solenoid R¹⁵ which during the test period is open, and thus test relay R¹¹ has its circuit open at all points and the design of the device as a whole is that no energization of that relay may result when the line selected is in a condition of disuse and subject to use in the connection now being established. 100

(2) The relay R¹² is energized over the path B, 42, 56, R¹², 57, 46, 47 and ground. By the closure of the left-hand armature of relay R¹², circuit is formed through elements B, 42, 56, 59 armature of R¹², 60, winding of R¹³, 61, switch s⁶ and ground, energizing relay R¹³ which locks itself energized over the circuit B, 42, 43, armature and inner contact of relay R¹³, winding of relay R¹³, 61, s⁶ and ground. This energization of 105 trunk-connecting relay R¹³ connects the conductors 23-24 of the trunk through to the outer contacts of the ringing relay R¹⁴ and through to the wiper s'. This furnishes a path through test relay R¹¹ as follows: B, 110 42, 62, R¹¹, 63, talking conductor to left-hand armature of R¹⁴, back contact and talking conductor to armature of energized relay R¹³, conductor 23, winding of relay R⁶ and ground; however, this circuit is adapted 115 to be opened by the attraction of the armatures of relay R¹⁴ and it is the function of the connector switch that the opening of this circuit at R¹⁴ shall succeed its closing at R¹² by a time limit so small that restoration of 120 the connector switch is not permitted. It will be noted in the study of this time element that the test relay R¹¹ must attain the degree of energization required to attract its armature, must swing its armature 125 130

through its full travel to close its contact and that subsequently to the closure of the contact of R^{11} the release magnet s^6 must reach the required degree of magnetization 5 and must overcome the inertia of its armature and move it through some definite arc before the release of the switch S will be effected. Since the circuit of the test relay R^{11} from the wiper s' to ground through the 10 relay R^6 of the same connector is at best only momentarily closed, this closure being during the instant after the operation of relay R^{13} and before the operation of R^{14} , it follows that the series of necessarily consecutive operations just traced with respect to the release magnet cannot occur during this 15 very short interval, and therefore no false test resulting in a consequent improper release occurs. The commutator X , as has 20 been mentioned, is carried upon the shaft which carries the number wheels and commutator devices Q^0 , Q , Q' , Q^2 , etc., and the commutator X is adjusted angularly with respect to those wheels so that the conducting 25 portion of X is in electrical connection with its brush at the time that the energization of the relay R^{13} occurs. It is seen that by the closing of contacts of R^{13} , by which current flow through relay R^{11} was permitted, current was simultaneously provided for 30 through path B , 42, X , winding of R^{14} , contact and armature r^{13} , 68, 50, r^{10} , 51 and ground. Thus current begins to flow through the winding of relay R^{14} the same 35 instant that current begins to flow through the winding of relay R^{11} , and, assuming equal speed in the operation of armatures, relay R^{14} will have moved its armature and will have broken its back contact, thereby 40 cutting off current from relay R^{11} , in ample time to prevent the restoration of the switch S by operation of release magnet s^6 , the break at the armature of R^{14} probably occurring in time to prevent any contact whatever 45 at the armature of relay R^{11} . Thus a test condition is maintained with the test wiper s' isolated from the winding of relay R^6 by the break at the armature of relay R^{14} , and the design and adjustment of the 50 commutator X shall be such that the relay R^{14} is held energized throughout the maximum period occupied by generator-selection impulses and until the opening of the circuit 55 of the test relay R^{11} by the opening of the switch 62 upon release of the armature of the solenoid R^{15} . The armature of the solenoid R^{15} is sluggish and does not open the switch 62 between the generator-selection impulses, so that the test circuit here described is maintained continuously during the period of 60 generator-selection.

Leaving the various parts of apparatus in the condition now considered, we will follow the action of the apparatus in response to 65 the generator-selection impulses. In the in-

stance assumed, since station No. 3 is to be called three battery impulses will be received over the wire 23 operating the armature of the relay R^6 successfully three times, which in turn acts over the path 47, 46, 57, 70 R^{12} , etc. to operate the armatures of relay R^{12} in succession three times. The armature r^{12} through its front and back contacts effects the selection of the desired ringing generator as follows: Upon attraction of r^{12} by the first generator selection impulse, it makes electrical connection with its inner contacts, but inasmuch as the wire 64 is open at the armature of relay R^{19} no complete circuit is closed. Upon the release of the armature r^{12} at the cessation of the first generator-selection impulse, circuit is closed through elements B , 42, 43, contact of R^{13} , 60, r^{12} , 65, contact of R^{16} , winding of R^{19} and ground, energizing relay R^{19} which locks over the circuit B , 42, 43, contact of R^{13} , 60, 69, armature and contact of R^{19} , winding of R^{19} and ground. If but one generator-selection impulse were received, the generator G would remain in connection with conductor 40 ready for connection through conductor 41 to the contact of the ringing relay R^{14} . At the beginning of the second generator-selection impulse, relay R^6 is energized and armature r^{12} is attracted, closing circuit through elements B , 42, 43, contact of R^{13} , 60, r^{12} , 64 closed contact of lower armature of relay R^{19} , back contact of relay R^{20} , winding of relay R^{16} and ground, energizing relay R^{16} which then locks over the circuit B , 42, 43, contact of R^{13} , 60, 69, armature contact and winding of R^{16} . Upon the cessation of the second generator-selection impulse, the armature r^{12} is released, closing circuit over B , 42, 43, contact of R^{13} , 60, r^{12} , 65, closed contact of lower armature of energized relay R^{16} , back contact of lower armature of unenergized relay R^{17} , winding of relay R^{20} and ground, energizing relay R^{20} , which then locks itself through its own contact by current received over conductor 69 to ground as in the case of relays R^{16} and R^{19} . If no more generator-selection impulses were received, the effect of the two impulses thus far followed would be to leave generator G connected to conductor 40 through contact of energized relay R^{16} , that being the proper generator for ringing the second station on a party line. At the beginning of the third and last generator-selection impulse, the armature r^{12} is again attracted, closing circuit over elements B , 42, 43, contact of R^{13} , 60, r^{12} , 64, closed contact of energized relay R^{19} , closed inner contact of energized relay R^{20} , closed outer contact of unenergized relay R^{21} , winding of relay R^{17} and ground, energizing relay R^{17} , which then locks itself by current through its own contact and winding over conductor 69 to ground. Upon the 110 115 120 125 130

cessation of the third and last generator-selection impulse, the armature r^{12} is released, closing circuit through elements B, 42, 43, contact of R^{13} , 60, r^{12} , 65, closed inner contacts of energized relays R^{16} and R^{17} , closed outer contact of unenergized relay R^{18} , winding of relay R^{21} and ground, energizing relay R^{21} which then locks itself by current through its own armature contact and winding from conductor 69 to ground. This leaves relays R^{16} and R^{17} energized and leaves relay R^{18} unenergized, thus effecting the connection of generator G^2 to the conductor 40, and as the generator-selection impulses now cease, solenoid R^{15} releases its armature, opening the circuit of the test relay R^{11} and closing the circuit between conductors 40—41, thus connecting the selected generator G^2 over conductor 41 to the inner contact of the left-hand armature of ringing relay R^{14} and thus through the upper wiper s' and to the line conductor of the selected line to ring the third station upon the party line selected.

The ringing will continue until the insulated portion of the commutator X passes under the brush of that commutator when the circuit of the winding of relay R^{14} will be interrupted and by release of that relay's armature the circuit from the wiper s' will be removed from the generator and carried to relays R^7 and R^6 respectively. The line selected will be subjected alternately to periods of ringing when the relay R^{14} is energized and to periods of non-ringing when the relay R^{14} is deenergized. Upon the answering of the called sub-station, or of any sub-station upon that party line, during a period of non-ringing, current immediately will flow through elements B, 42, winding of R^7 , 24, lower s' , line conductor, substation bridge, return line conductor, upper s' , 23, winding of R^6 and earth, energizing R^6 and attracting its armatures.

By the operation of the left-hand armature of R^6 , circuit is closed through elements B, 42, left-hand armature and inner contact of R^6 , winding of R^{10} , 54, contact and left-hand armature of R^7 , 55 and ground, energizing R^{10} which then locks over the circuit B, 42, right-hand armature and contact of R^{10} to winding of R^{10} , 54, contact and armature of R^7 , 55 and ground. By energization of relay R^{10} , ground is taken off of wire 50 so that ringing relay R^{14} may not again be energized. Also by the energization and locking of R^{10} the relay R^6 is released and remains released throughout the remainder of the connection. This is the condition of conversation and continues until the hanging up of the telephone and the breaking of the substation bridge upon the called line.

Upon the hanging up of the telephone and the breaking of the substation bridge upon 65 the called line, disconnection of the switch S is effected as follows: Circuit is interrupted over the return wire of the line and through relay R^6 to ground, releasing the armatures of relay R^6 , but current continues through elements B, 42, winding of R^7 , 24, 70 lower wiper s' , and the sleeve side of the connected line and the winding of its cut-off relay M' to ground, maintaining the energization of the relay R^7 . By the release of the left-hand armature of relay R^6 a release relay circuit is established through elements B, 42, left-hand armature and outer contact of deenergized relay R^6 , winding of release relay R^{22} , inner contact and armature r^{10} of relay R^{10} , 51 and ground, energizing release relay R^{22} which, by closing its contact, energizes release magnet S^6 , which effects immediate restoration of all parts of the switch S to the normal position of disuse.

A consideration of test conditions during the process of the connection is desirable. When the test wiper or upper wiper s' connects with the test conductor of the selected line, no action is taken either to test for busy or to place a busy test upon the line until the wheels Q' , Q^2 , Q^3 , etc., have in due course of progress begun to send the generator-selection impulses; at this time, by the action of the solenoid R^{15} , the selected line is tested for busy condition, the testing for busy condition being continued throughout the receipt of the generator-selection impulses and the line being left unguarded against connection by other connectors; at the close of the generator-selection impulses the test relay is taken off and the ringing generator is substituted. From this time a busy test guard condition is placed upon the test conductor of the selected line, being alternately the potential of the selected ringing generator when the relay R^{14} is energized, which is sufficient to energize any relay R^{11} which may test the line during the interval of ringing, and between the intervals of ringing the busy test consists of the ground circuit through the relay R^6 . If the line thus connected with be tested for busy condition by some other connector attempting a connection with it and during the interval of deenergization of ringing relay R^{14} , a current will flow from the connector then testing to the test conductor of the line, thence through the test wiper of the connector of Fig. 3 holding the line, and through back contact of relay R^{14} , front contact of R^{13} , 23, and winding of R^6 to ground. This current will be of sufficient strength to energize the test relay R^{11} of the distant connector attempting to take the line being held, and this will effect disconnection of that connector but it will not be of sufficient strength to energize the relay R^6 inasmuch as by the energization and subsequent deenergization of that relay, the said testing current would also restore the holding con-

necter of Fig. 3 to its normal condition of idleness.

It will be observed that the circuit during conversation is the same as the standard manual talking circuit, having a single pair of condensers, C, and the main battery B bridged across each side of these condensers through a pair of relays.

In Figs. 4 and 5 I have shown in diagram 10 a form of my invention differing from the foregoing form principally in two respects. In the first place instead of having a plurality of sets of pens on the sending machine, one for each row of buttons of the key 15 set, a single set of pens common to all the rows is used together with switching devices which shift the set from row to row in the order of transmission of the impulses. In the second place, a plurality of key sets are 20 associated with the same sending machine, and in addition are supplied with impulses through the same set of contact pens. All of the parts in Figs. 4 and 5 of the same 25 general character as those in Figs. 1 and 2 bear the same reference characters.

Referring particularly now to Fig. 5, the sending machine of this modification comprises in detail an impulse generating wheel W provided with teeth 100 at regularly recurring intervals around its periphery and preferably separated at their points by fillings 101 of insulating material. This wheel W is connected with positive battery B by conductor 102 and brush 103 bearing on 30 shaft 104 on which the wheel is mounted. Bearing on the periphery of the wheel is a brush 105 connecting by conductor 106 and brush 107 with shaft 108 of a set of wheels Q' to Q⁵ of the sending machine. These 35 wheels, instead of having teeth on their peripheries are provided each with a plurality of contact cam or wiper surfaces 109 arranged to make contact as the wheels revolve with the associated fixed contact pens 110. In the form shown there are provided 40 four of the contact cams 109 on each wheel and spaced apart 90°. From disk Q' to disk Q⁵, the cams 109 are of progressively increasing length. Those on wheel Q' are 45 of a length sufficient to make contact with the associated pen 110 for a period of one impulse, those on wheel Q² of sufficient length to maintain contact with the associated pen 110 for a period of two impulses, 50 those of disk Q³ for a period of three impulses and so on, the number of impulses being measured by the number of teeth 100 which pass under brush 105 or wheel W, wheel W and disks Q' to Q⁵ being driven in 55 synchronism, though insulated from each other. Disk Q connected with battery through a conductor 102 and brush 111 and on the periphery of which bear contact pens 60 Q⁵ and Q⁶, is of the same character as the disk Q of Fig. 2. Disk Q'' however is in-

sulated from shaft 108, connected to ground through conductor 112 and brush 113 and provided with four contact cams 114 at right angles to each other and of a length sufficient to make contact with the associated pen 115 for a period of approximately one impulse. On the other end of shaft 108 and preferably insulated therefrom and supplied with battery through conductor 102 and brush 116 is a series of four disks r q' 75 to r q⁴, each of which bears a single contact cam 117 somewhat less than a quadrant in extent and each displaced from the other by 90°. These cam contacts 117 make contact with pens 118 connected respectively with 80 impulse group relays r' to r⁴, the arrangement being such that the relays r' to r⁴ are successively energized each for a period somewhat less than a quarter of a revolution of the disks of the sending machine. 85 While there are shown herein disks having cam contacts in a 90° relation, obviously the number of cam contacts per disk, and their relations may be varied at will and is to be chosen in accordance with the number of 90 groups of impulses to be sent. Associated with this sending machine is a plurality of key sets, designated respectively I, II and III. Each set consists of four rows K¹ to K⁴. The contacts made by the push buttons 95 of the rows are substantially the same as those made by rows K' and K⁶ of Fig. 2, but instead of being connected by rows each with a set of contact pens 110, the rows of all the key sets are multiplied commonly to 100 contact pens 110. On the other hand the common conductors c' to c⁴ of each key set I, II and III are connected each to an individual contact in one of the impulse group relays r' to r⁴ in the order of the rows, all 105 conductors c' of rows K' extending to contacts in relay r', all conductors c² of rows K² extending to contacts in group relay r², etc. Corresponding contacts of the relays r' to r⁴ are connected with common conductors C', C² and C³ which extend to the cut-on and cut-off relays R⁴, R⁵ of Fig. 5, and of 110 which relays there are three groups, one for each key set I, II and III, and controlled from disk Q in essentially the same manner 115 as in the form of Fig. 2. Instead, however, of initial closure of the circuit of relay R⁴ from the last row K in which a push button is depressed, special starting keys S k' S k², S k³ are used, one for each key set, 120 and each adapted to initially energize the relay R⁴ of the corresponding group R⁴, R⁵. It is of course apparent that conductors C', C² and C³ correspond to conductors 32 and 33 of Fig. 2. Four rows of K push buttons 125 are provided in each key set, but obviously this may be varied at will and depends solely upon the number of groups of controlling impulses to be transmitted, and the number of groups of impulses depends in 130

turn upon the number of switching operations incident to the system.

Referring now to Fig. 5, it will be seen that the arrangement of the individual groups of cut-on and cut-off relays R^4 , R^5 differs from that of Fig. 2 in that the relays R^5 are pulled up through contacts r^8 on relays R^4 instead of the closure of the circuit directly by the starting keys S h corresponding to contacts k^6 of Fig. 2. Conductor 119 connected with brush 115 of disk Q'' is multiplied to contacts r' of relays R^4 . Through individual keys or plugs Y' , Y^2 , Y^3 , conductors 15, 16 of the groups R^4 , R^5 15 may be individually connected with conductors 15', 16' which are connected permanently or temporarily with a link or trunk circuit such as that shown in Fig. 1, and in the same manner as conductors 15 20 and 16 of Fig. 1 connected with that circuit. An additional contact r^{10} on each of the relays R^5 is arranged normally to close the circuit of a lamp 120 through contacts 121 closed when key Y is pressed. Conductors 15, 16 and 122 are multiplied to other sets of keys Y' , Y^2 , Y^3 associated with other links or trunks, in the manner illustrated in connection with the link circuit of Fig. 1, there being provided a set of lamps 120 for 30 each set of keys Y and a set of keys Y for each link or trunk. The operation of this modification is as follows: Impulses are continuously generated by the continuous revolution of wheel W of the sending machine. 35 The operator answering a call after connecting an idle cord circuit with the calling line obtains from the subscriber the number he desires. Guided by the lamps 120 which are illuminated when the corresponding key sets 40 are busy, she picks out an idle key set and sets up on the rows of buttons K the number of the called line, immediately thereafter (if not immediately before) pressing the corresponding key Y connecting the selected key set with the cord circuit, and then 45 pressing the corresponding starting key S h . This at once energizes the corresponding relay R^4 , which pulling up locks up over conductor 123 and pen q^6 , disk Q and conductor 50 102 to battery. Simultaneously relay R^4 closes the circuit of relay R^5 by its contact r^8 , and relay R^5 locks up over conductor 124 and by pen q^5 and the path just traced from pen q^6 to battery. From this point on, the 55 operation of the relays R^4 , R^5 is essentially the same as the operation of the same group in Fig. 2. The operation of the sending machine and the multiply fed key sets, however, is different. Relay R^4 having fallen back and the conductors 15, 16 having been closed to the cord circuit, the rows K^1 of each key set are simultaneously associated with the impulse conductors C' to C^3 by means of the energization of impulse group 60 65 relay r' , the wiper 117 of this relay having

engaged the pen 118. Impulses generated by the wheel W are then transmitted by way of the disk of the group Q' to Q^5 connected by pen 110 with the individual button of the row K' which is pressed, through 70 the contacts of this button, by common conductor c^1 , by that one of conductors C' , C^2 , C^3 corresponding to the key set selected, to the contacts of the corresponding group R^4 , R^5 and the corresponding key Y to the 75 link circuit. This group having been transmitted, in a period of time somewhat less than a quarter revolution of the sending machine, the impulse group relay R' is deenergized, and a shifting impulse is transmitted from ground by way of conductor 80 112, brush 113, cam 114 and pen 115 of wheel Q'' over conductor 119 and by conductor 16 to the opposite side of the link. The first group of selecting impulses having directed the selecting switch through its primary operation, the shifting impulse starts the switch on its secondary operation to find an idle trunk in the succeeding group. Sufficient time having elapsed for this purpose, impulse group relay r^2 is energized by 85 the closure of its circuit through contact 117, 118 of disk r q^2 , its relay connecting with common conductors C' , C^2 , C^3 the rows K^2 of the key sets with the result that the second digit of the number is translated into 90 impulses transmitted over the path just described and through the first selector switch to the second with the same result. Thereafter, the relay r^2 having been deenergized, 95 100 the second shifting impulse follows and so on. The fourth group of impulses resulting from the translation of the number set up on the rows K^4 may be used for party line selection. From this it will be seen that 105 from the one sending machine it is possible to supply impulses to a multiple number of key sets, and to use this multiple number of key sets variably with a multiple number of link circuits or trunks without any confusion whatsoever. The lamps 120 indicate at 110 all times the busy or idle condition of the key sets, and the transmission of the sets of impulses for any number is commenced always from the same point as determined by 115 the wheel Q and the relays R^4 , R^5 . The transmission simultaneously of a plurality of sets of controlling impulses proceeds 120 without disorder of any kind.

In Figs. 6, 7 and 8 I show the mechanical 125 construction of the rows of buttons in the key sets. As illustrated there are ten buttons, 1 to 9 and 0, while in the diagrams I have illustrated only 5. This diagrammatic illustration is simply for convenience, there being provided ten buttons in each row to represent the ten digits. These buttons are mounted on the upper ends of push rods 125 extending through upper and lower plates 126 and 127. The plate 127 is composite, 130

and composed in its main body of insulating material in which are socketed or embedded the contacts k' , etc. which control the circuits of the sending machine. On each plunger 125 just beneath plate 126 is fastened a block 128 provided on one side with an insulating lug 129 bearing through a beveled face on the outturned end of one of the contacts k' , while on the opposite side the rod 128 is provided with a dog 130 which bears by its bevel face on a pin 131 in the bar 132. This bar is slidably mounted in uprights 133 which connect the upper and lower plates 126-127 and so arranged that whenever a key is depressed, dog 130 acting on pin 131 moves the bar to the left, whereupon the lug 130 having passed the pin 131, bar 132 is moved back to the right by pressure of the spring 134 and thereafter holds the key in depressed position, in which the contacts k' are closed as illustrated in the third key. Spring 135 normally bias the keys upwardly so that when any key is pressed down, the key at that time latched is released, whereby as hereinbefore mentioned, it is impossible to have two or more keys closed at the same time without holding a finger on each key. Confusion in the number of impulses is thereby avoided.

In detail construction, the insulating main body of plate 127 is embraced by metallic side plate 136 into which the upright end members 133 are entered in lateral sockets, the ends being riveted over. The upper ends of 133 are entered in vertical sockets in plate 126 and likewise riveted over. Stop pins 137 are passed transversely of plates 136 immediately below the ends of plungers 125.

While I have shown and described the best forms of my invention now known to me, it is of course well understood that my invention may be embodied in many forms without departing in any wise from its generic spirit. I desire to cover all such forms in the annexed claims.

I have not deemed it necessary to show the selector and connector circuits of the larger system to which the form of Figs. 4 and 5 is especially adapted, since my invention does not have to do with the number of trunks used.

It is contemplated by my invention and a part of the same, that the keys of the sets Y' and Y'' are to be formed in an essentially similar manner to those of the rows K as illustrated in Figs. 6 to 8 and furthermore that the same latching means is to be used in connection with these keys Y' to Y'' , whereby when any one of them is pressed the other is released. However this feature may be omitted its use being optional.

By the term "latent signal transmitter" I mean a transmitter which the setting act does not directly or immediately operate as

the unit digits or other code indications are set up, but in which the signal is stored up latent until its character is fully completed and some further act or condition supervenes to release it. This further act may be the closure of the last button of the ringing set as described or some other occurrence due to the operator or to the condition of the circuits. The importance of this concept lies in the fact that the operator is not required to wait for the fragmentary transmission of each part of the code signal before setting up the next part as in the use of single digit or direct acting transmitters. The total operator time per connection thus saved is several seconds.

What I claim is:—

1. In a telephone system, a continuously driven multiple signal impulse transmitting device, together with automatic switches for connecting lines, controlled by said transmitting device.
2. In a telephone system, a system of continuously driven commutators, producing impulses continuously, and a bank of selecting keys adapted to select from said commutators the impulses desired for any specific selection, together with automatic line connecting switches controlled thereby.
3. In a telephone system, a system of continuously driven commutators producing impulses continuously, and a plurality of impulse selecting devices adapted to select from said commutators the impulses desired for any specific selection together with automatic line connecting switches controlled thereby.
4. In a telephone system, a system of continuously driven commutators producing selective impulses continuously, and a plurality of sets of selecting keys adapted to select from said commutators the impulses desired for any specific selection, together with automatic line connecting switches controlled thereby.
5. In a telephone system, a system of continuously revolving commutators producing in each revolution a complete cycle of selective impulses in the maximum required for any possible selection; and means for excerpting from any cycle the impulses required for any specific selection, together with automatic line connecting switches controlled thereby.
6. In a telephone system, a system of continuously revolving commutators producing in each revolution a complete cycle of selective impulses in the maximum required for any possible selection; and a bank of selecting keys adapted to excerpt from any cycle the impulses required for any specific selection, together with automatic line connecting switches controlled thereby.
7. In a telephone system, a system of continuously revolving commutators producing

- in each revolution a complete cycle of signaling impulses in the maximum number required for any possible selection; and a plurality of sets of keys associated with said system of commutators and adapted to excerpt from any cycle of impulses the specific impulses required for any specific selection, together with automatic line connection switches controlled thereby.
8. In a telephone system, a pair of bus conductors leading to an operator's keyboard; a source of current; a plurality of keys; a commutator device, auxiliary conductors leading from said keys to said commutating device and arranged in said commutating device to receive impulses from said source of current varying with the different auxiliary conductors, said keys being adapted to connect a limited plurality of said auxiliary conductors to one of said bus conductors.
9. In a telephone system, a system of continuously driven commutators producing selective impulses repeatedly, and a bank of selecting keys adapted to select from said commutators the impulses required for any specific selection, and in a predetermined order, together with automatic line connecting switches controlled thereby, substantially as described.
10. In a telephone system, a plurality of subscribers' lines, automatic switching apparatus, means for connecting said lines to said automatic switching apparatus, a mechanical number recording device whereon an operator may record individually a plurality of digits of the number of the line desired, and independently and differently characterized electrical circuits selectively associated with said recording device and including automatic means whereby the mechanically recorded directory digits are subsequently translated consecutively into corresponding controlling impulses whereby the automatic switching apparatus is controlled to complete the connection of the calling line to the line desired.
11. In a telephone exchange system, a plurality of lines to be interconnected, a plurality of automatic switches for effecting the interconnection, but normally disconnected from the lines, means for connecting the switches to calling lines, and switch controlling means comprising an operator's keyboard having keys or buttons arranged in groups corresponding to the digits of the number to be called and a plurality of independently and differently characterized electrical control circuits governed by the keys, with means to connect the keyboard to any of said switches for actuating the same.
12. A semi-automatic telephone exchange system comprising a plurality of lines to be interconnected, a number of automatic switches less than the number of lines, and a number of operators' sending or controlling devices less than the number of switches, with means to bring a sending device into temporary association with the various switches for actuating the same, each sending device comprising a composite variable signal wheel, a motor for driving the same, and a keyboard having a plurality of digital rows of keys connected with the wheel for setting up the number wanted, substantially as described.
13. In a telephone exchange system, a plurality of lines to be interconnected, a number of trunk circuits less than the number of lines, automatic switches for connecting said trunk circuits with called subscribers' lines, an operator's sender for controlling said automatic switches, said sender comprising a number wheel and a plurality of rectilinear rows of selective buttons, each row having a limited number of buttons coöperating therewith to determine the digits of the number transmitted, and means for connecting calling lines with said trunks, substantially as described.
14. In a telephone system, a plurality of telephone lines; a link circuit; a constantly revolving generator of signal impulses; automatic selective switches adapted to be actuated by said impulses; means for connecting said link to a calling line; means for connecting said link to said generator of signal impulses; and means for connecting said link to an automatic selective switch.
15. In a telephone system, trunks, automatic switches, a system of continuously driven commutators, producing impulses continuously, and a bank of selecting keys adapted to select from said commutators the impulses required to actuate said switches for any specific selection.
16. In a telephone system, automatic connecting switches, trunks to said automatic connecting switches, a system of continuously driven commutators, producing selective impulses continuously, and a bank of selecting keys adapted to select from said commutator the impulses desired for the operation of that trunk's selector switch.
17. In a telephone exchange system, a plurality of subscribers' stations, a central station, line-wires passing from the sub-station to the central station, automatic switches for interconnecting the lines, latent signal transmitters at the central station comprising continuously revolving commutator devices, a number selecting bank of push buttons; and devices for connecting to the said automatic switches for actuating said switches.
18. In a telephone exchange system, a plurality of subscribers' stations, a central station, line-circuits interconnecting them, automatic switching devices less than the number of lines, at the central station, and latent signal transmitters also at the central station

- comprising continuously revolving commutator devices and a bank of signal-varying push buttons adapted to be controlled by operators thereat for setting the switches.
- 5 19. In a telephone exchange system, a plurality of subscribers' lines, a central office therefor, automatic switching apparatus at said central office, an operating device at the central office consisting of constantly driven commutators associated with signal-selecting push buttons and common to a plurality of the switches thereof, and switching means controlled by an operator to connect said device to any desired switch or switches so as to operate the same.
- 10 20. In a telephone exchange system a plurality of automatic switching devices, and a controller consisting of constantly driven signaling commutators and an associated bank of signal selecting push buttons and common to all of them, together with means to apply the same to any desired switch for the purpose of actuating the same.
- 15 21. In a telephone exchange system a plurality of line-circuits, a plurality of automatic switches, and a common impulse generator or commutating device continuously driven and continuously producing uniform repeated cycles of automatic-switch controlling impulses, and a bank of push buttons adapted to excerpt from a complete cycle any desired combination of impulses required for properly operating one of said automatic switches, together with means whereby selected operating impulses therefrom may be sent to any desired switch or switches for the purpose of operating the same.
- 25 22. In a telephone exchange system a plurality of subscribers' lines, a plurality of automatic switches, a variable signal transmitter consisting of continuously rotating commutators and associated selecting push buttons and common to said switches, and contact devices whereby said variable signal transmitter may be connected to said switches so as to supply the same with any desired number and arrangement of impulses to produce a given connection.
- 30 23. In a telephone exchange system, a subscriber's line, and signal devices responsive to calls thereover, an automatic switch associated with said line, and an operator's controlling device consisting of a set of impulse selecting push buttons associated with a continuously operating impulse producing mechanism for actuating said switch to effect any desired connection.
- 35 24. In a telephone exchange system, a central office equipment comprising a plurality of automatic switches, a multiple commutating device common to a plurality of said switches, and operators' keys for selectively connecting said commutating device to the switches.
- 40 25. In a telephone exchange system, a plurality of automatic switching devices, trunk lines therefor, a constantly driven multiple signal transmitter common to said switches, and operators' keys for selectively connecting the said signal transmitter to said automatic switching devices.
- 45 26. In a telephone exchange system a plurality of automatic switches, a common variable signal transmitter comprising a plurality of independently and differently characterized electrical control circuits, switching keys for selectively connecting the same to the switches, and a trip device to disconnect the same after a particular signal has been completed.
- 50 27. In a telephone exchange system, a plurality of automatic switches, a common variable signal device comprising a plurality of impulse transmitters, operating switching keys for selectively connecting the elements of said transmitter to the automatic switches as desired, and a trip device controlled in the operation of the transmitter for disconnecting the same after each connection when the selected signal has been completely transmitted to the switches.
- 55 28. In an automatic telephone exchange system, a plurality of line-circuits and a plurality of automatic switches for interconnecting the same, a common constantly driven multiple signal and impulse generator or commutator, selective keys controlled by an operator and adapted to be set so as to determine a particular number or group of numbers, a starting device automatically controlled in the operation of the generator or commutator to connect the same through the keys to the switch associated therewith, so as to transmit the selected number in order; and a disabling device thereafter controlled by the generator or commutator to effect disconnection of said generator from the switch when the selected numbers have been transmitted complete.
- 60 29. In a telephone exchange system a plurality of automatic switches for interconnecting lines, and a controlling device therefor comprising the following instrumentalities: a set of contact makers and contacts coöperating therewith, so as respectively to produce groups of current impulses from 1 to 10, a group of ten selective keys or switches, each when actuated adapted to select and connect with the corresponding contact maker, and means to effect disconnection when a complete number has been transmitted.
- 65 30. In a telephone exchange system a plurality of automatic switches for interconnecting lines and controlling means therefor comprising the following instrumentalities: a multiple contact sender having elements adapted to produce current impulses in groups from 1 to 10, selective keys in groups

adapted to receive said impulses in proper sequence when set, a starting device for completing operative connection from said multiple contact sender through the selective key or keys to the desired switch or switches, becoming operative at the beginning of a sequence, and a stopping device for effecting disconnection of the previously connected switch or switches from said multiple contact sender in any particular case at the end of the sequence of impulses.

31. In a telephone exchange system a plurality of automatic switches for interconnecting lines, and a controlling device therefor comprising the following instrumentalities: a constantly driven common multiple number transmitter having ten elements with associated contacts adapted to produce impulses from 1 to 10, respectively, a group of selective keys adapted to be set by an operator to partially connect the selected elements to a switch circuit, a relay for completing the connection, a starting device adapted to control said relay, said starting device acting at the beginning of a sequence of impulses produced by the transmitter only, and means controlled by the operator in setting the selective keys, to connect said relay so that it will be actuated by said starting device at the beginning of the next succeeding sequence of impulses.

32. In a telephone exchange system, a plurality of subscribers' lines, one or more of said lines having a plurality of substations upon it, automatic switching apparatus for interconnecting the lines, selective signaling means associated with said switching apparatus, an automatic impulse transmitter, switching means controlled by an operator to connect the same to the automatic switching apparatus in order to select the desired line, and means also controlled by an operator to connect the same to the selective signal means whereby the latter will be automatically actuated to select and signal the desired substation, substantially as described.

33. In a telephone exchange system, a plurality of subscribers' stations; a central station; line wires passing from the substations to the central station; automatic switches for interconnecting the lines; latent signal transmitters at the central station comprising revolving commutator devices and a number selecting bank of push buttons; and devices for connecting said signal transmitters to said automatic switches for actuating said switches, substantially as described.

34. In a telephone exchange system, a plurality of subscribers' stations; a central station; line wires passing from the substations to the central station; automatic switches for interconnecting the lines; latent signal transmitters at the central station comprising

revolving commutator devices and a number selecting bank of push buttons; and devices for connecting said signal transmitters to said automatic switches for actuating said switches, substantially as described.

35. In a telephone exchange system, a plurality of subscribers' stations; a central station; line wires passing from the substations to the central station; automatic switches for interconnecting the lines; latent signal transmitters at the central station comprising continuously revolving commutator devices and a number selecting bank of keys; and devices for connecting said signal transmitters to said automatic switches for actuating said switches, substantially as described.

36. In a telephone exchange system, a plurality of subscribers' stations; a central station; line circuits interconnecting them; automatic switching devices less than the number of lines at the central station; and latent signal transmitters also at the central station comprising revolving commutator devices and a bank of signal varying push buttons adapted to be controlled by operators thereat for setting the switches, substantially as described.

37. In a telephone exchange system, a plurality of subscribers' stations; a central station; line circuits interconnecting them; automatic switching devices less than the number of lines, at the central station; and latent signal transmitters also at the central station comprising a bank of signal varying keys adapted to be controlled by operators thereat for setting the switches, substantially as described.

38. In a telephone exchange system, a plurality of subscribers' lines; a central office therefor; automatic switching apparatus at said central office; an operating device at the central office consisting of commutators associated with signal selecting push buttons and common to a plurality of the switches thereof, and switching means controlled by an operator to connect said device to any desired switch or switches so as to operate the same, substantially as described.

39. In a telephone exchange system, a plurality of subscribers' lines; a central office therefor; automatic switching apparatus at said central office; an operating device at the central office consisting of constantly driven commutators associated with signal selecting devices and common to a plurality of the switches thereof; and switching means controlled by an operator to connect said device to any desired switch or switches so as to operate the same, substantially as described.

40. In a telephone exchange system, a plurality of automatic switching devices; and a controller consisting of signaling commu-

tators and an associated bank of signal selecting push buttons and common to all of said automatic switching devices, together with means to apply the same to any desired 5 switch for the purpose of actuating the same, substantially as described.

41. In a telephone exchange system, a plurality of automatic switching devices; and a controller consisting of constantly driven 10 signaling commutators and associated signal-selecting devices and common to all of said automatic switching devices, together with means to apply the same to any desired switch for the purpose of actuating the 15 same, substantially as described.

42. In a telephone exchange system, a plurality of subscribers' lines; a central office and a plurality of automatic switches thereat; together with an impulse generator or 20 number transmitted consisting of a plurality of independently and differently characterized electrical control circuits including impulse generating devices associated with a bank of circuit selecting push buttons 25 and common to said switches, and means whereby an operator may connect the said transmitter to send selected controlling impulses to any desired switch, substantially as described.

43. In a telephone exchange system, a plurality of subscribers' lines; a central office and a plurality of automatic switches thereat; together with an impulse generator or number transmitter consisting of 30 constantly driven impulse generating devices associated with a bank of impulse selecting keys and common to said switches; and means whereby an operator may connect the same to send selected controlling impulses 35 to any desired switch, substantially as described.

44. In a telephone exchange system, a plurality of subscribers' lines; a central office and a plurality of automatic switches 45 thereat; together with an impulse generator or number transmitter consisting of constantly driven impulse generating devices associated with impulse selecting means 50 common to said switches; and means whereby an operator may control the same to send selected controlling impulses to any desired switch, substantially as described.

45. In a telephone exchange system, a plurality of subscribers' stations; a central 55 station; line wires passing from the stations to the central station; automatic switches for interconnecting the lines; latent signal transmitters at the central station comprising commutator devices and a number 60 selecting bank of keys; and devices for connecting said signal transmitters to said automatic switches for actuating said switches, substantially as described.

46. In a telephone exchange system, a 65 plurality of subscribers' stations; a central

station; line circuits interconnecting them; automatic switching devices less than the number of lines at the central station; and latent signal transmitters also at the central station comprising commutator devices and 70 a bank of signal varying keys adapted to be controlled by operators thereat for setting the switches, substantially as described.

47. In a telephone exchange system, a plurality of subscribers' lines, a central station in which said lines terminate, automatic switches for interconnecting the lines, and latent signal transmitters at the central station comprising mechanism for transmitting impulses, with means selectively controlled by the operators to determine the numbers, and connections from said latent signal transmitters to the switches, whereby the operators may predetermine the movement of the switches, without being compelled to progressively follow or direct the 80 same.

48. In a telephone exchange system, a plurality of subscribers' lines, automatic switches for interconnecting the lines, means whereby an operator may connect with the lines for purposes of conversation, and a latent multiple signal transmitter associated with the switches and controllable by the operator to predetermine the operation of the switches in selecting a number without requiring further action on the part of the operator.

49. In a telephone system, a system of continuously driven commutators producing impulses continuously, and a plurality of sets of selecting keys adapted each to select from said commutators the impulses desired for any specific selection, together with automatic line connecting switches controlled thereby.

50. In a telephone system, a system of continuously revolving commutators producing in each revolution a complete cycle of selective impulses in the maximum required for any possible selection, and a plurality of sets of selecting devices, each adapted to excerpt from any cycle the impulses required for any specific selection, together with automatic line selecting switches controlled thereby.

51. In a telephone system, a plurality of pairs of bus conductors leading each to an operator's key board, a source of current, a plurality of sets of keys on said key board, a commutating device, auxiliary conductors leading from said sets of keys to said commutating device and arranged in said commutating device to receive impulses from said source of current varying with the different auxiliary conductors, said sets of keys being each adapted to connect a limited plurality of said auxiliary conductors to one of said bus conductors.

52. In a telephone exchange system, a

- plurality of lines to be interconnected, a plurality of automatic switches for effecting the interconnection but normally disconnected from the lines, means for connecting 5 the switches to calling lines, and an operator's key board having a plurality of sets of keys or buttons and a corresponding number of differently characterized switch control circuits selectively associated therewith, 10 the keys or buttons of each set of which are arranged in groups corresponding with the digits of the number to be called, together with means to connect any set of said keys or buttons and associated control circuits 15 to any of said switches for actuating the same.
53. A telephone exchange system, a plurality of lines to be interconnected, automatic switches for effecting interconnection but normally disconnected from the 20

lines, and an operator's key board for controlling the switches comprising a plurality of sets of keys or buttons, the keys of each set of which are arranged in groups corresponding to the digits of the number to 25 be called, independently and differently characterized electrical control circuits selectively associated with said sets of keys, together with means to connect any set of said keys with any of said automatic 30 switches and to therethrough associate with said switches said independently characterized control circuits.

In testimony whereof I affix my signature in presence of two witnesses.
